UNITED STATES PATENT OFFICE.

ANTON RUZICKA, OF CLEVELAND, OHIO.

MACHINE FOR ASSEMBLING OR SETTING THE SPRINGS IN SEPARABLE FASTENERS OR SPRING-STUDS.

1,262,099.

Specification of Letters Patent.

Patented Apr. 9, 1918.

Application filed June 18, 1917. Serial No. 175,346.

To all whom it may concern:

Be it known that I, ANTON RUZICKA, citizen of the United States, residing at Cleveland, in the county of Cuyahoga and State of Ohio, have invented certain new and useful Improvements in Machines for Assembling or Setting the Springs in Separable Fasteners or Spring-Studs, of which the following is a specification.

- 10 This invention relates to machines for assembling or setting the springs in separable fasteners or spring studs. These fasteners or press studs comprise two parts, a head part and a socket part, and the socket part 15 has a stud which is slotted at the sides, and is provided with a bent spring which projects through the slots in position to engage the head when the parts are snapped together.
- 20 A machine for making the parts of such fasteners is disclosed in the patent to Prym 921,160, and the device is especially adapted for use in a machine of that kind.

The object of the invention is to provide 25 improved means for placing the springs in the studs.

In the accompanying drawings—

Figure 1 is a side elevation of a part of a machine containing the invention;

30 Fig. 2 is a top plan view of Fig. 1;

Fig. 3 is a bottom plan view of the punch;

Fig. 4 is a vertical section of the punch;

Fig. 5 is a section on the line 5—5 of

Fig. 4;

35 Figs. 6, 7, 8 and 9 are sectional views showing the successive operations of the punch in placing a spring in the stud or fastener.

In the accompanying drawings—1 indicates a rotary table or conveyer disk for carrying the stud members or parts, and this corresponds to the disk 1 in the Prym patent referred to. 2 is a guide piece for the springs which are forced into the studs, and 45 3 is part of a feeding mechanism for feeding the springs into position over the stud member and under the punch, the springs being forced by the punch into the stud, the general operation being described in the patent referred to.

The present invention relates to the punch and the associated parts, and 4 indicates a shell which contains a hollow casting 5 the upper end of the bore 6 of which is threaded as indicated at 7 to receive a stud bolt

22 by which the punch is attached to its supporting and operating arm 21. The lower end of the bore in the casting is reduced as indicated at 8 and provided with a substantially semicircular extension or 60 neck 9 which depends below the shell 4. Slidable up and down in this neck is a spreading member 10, the lower end of which normally projects below the neck and the edge of which opposite the neck 9 is rounded 65 as indicated at 11, and the sides of which are flattened. The upper end of the member 10 has a hollow head 12 which stops against the shoulder 8a in the casting. The member 10 is also bored lengthwise and has 70 therein a reciprocating pin 13 with a head 14 at the top which stops against a shoulder in the hollow head 12. The pin 13 is pressed down by a spring 18 under a screw cap 19, and the punch member 10 is pressed down by 75 a spring 20 confined in the bore 6 above the head 12. The lower end of the pin 13 has a recess 15 to conform to the top of the projection 16 on the stud or fastener member 17. This projection is as stated slotted at 80 the sides as indicated at 30, and the purpose of the invention is to insert the springs 23 in the stud member with its ends engaging in said slots. The remaining parts will be understood from the following description 85 of the operation.

The spring carrier 3 carries the spring 23 which is held in a notch 24 therein and is moved forward over the guide arm to bring the openings in the spring carrier and guide 90 into alinement with the opening in the disk 1 which carries the stud member. The guide member 2 has an inserted ring 25 with sloping walls 26, and the stud member 17 is carried in a ring block 27 mounted in the disk 95 1. With the parts in registered position, as shown in Fig. 6, the punch is forced down by appropriate mechanism and the member 10 first spreads the arms of the spring 23, as shown in Fig. 7, and as shown in said figure the circular part of the spring 23 is of greater size or diameter than the neck 9. As the punch continues down to the position shown in Fig. 8 the sides of the spring are contracted by the sloping walls 26 and 100 engage in a slight groove 28 in the end of the neck 9. As the punch continues on down the spring is forced through the guide block 26 and down into the socket member 17 as 105 shown in Fig. 9, the pin 13 striking the top 110

of the stud 16 and yielding by compression of the spring 18, and the member 10 continues on down until it reaches the bottom of the socket member 17, thus forcing the arms of the spring 23 to a position below the head 16, the member 10 finally yielding against the tension of the spring 20 and permitting the neck 9 to finally carry the spring down into the bottom of the stud as shown in Fig. 9, in which position the arms of the spring slip into the slots 30 and the parts are assembled. The punch is then lifted and the dial turns for the next operation. The flattened sides of the plunger 10 fit flatly between or against the straight arms of the spring 23 and consequently do not tend to twist or distort said arms.

The device described is efficient in operation and enables the springs to be readily assembled in the stud members.

I claim:

1. A setting punch for the purpose described, comprising a pressing member with a hollow projecting segmental neck, a spring-pressed spreading member slidable lengthwise in the neck and normally projecting beyond the same, and a yielding center pin slidable lengthwise in said spreading member.
2. The combination with a holder for a stud member, of a tapered guide leading

thereto, and a setting punch adapted to force a curved spring through the guide and into said member, said punch having a yielding spreader projecting therefrom and adapted to be forced between the arms of said curved spring, for the purpose described.

3. The combination with a holder for a cupped fastener member having a central slotted stud, of means to insert a curved spring in said member, comprising a tapered guide leading to said holder and adapted to contract the spring; a setting punch adapted to force the spring through said guide and into said member, and a yielding spreader projecting from the punch and adapted to spread the free ends of the spring to pass the same over the slotted stud.

4. A setting punch for the purpose described, comprising an outer neck segmental in cross section, a yielding hollow spreader with flattened sides working in said neck and projecting beyond the side face thereof, and a central yielding pin working lengthwise in said spreader.

In testimony whereof, I do affix my signature in presence of two witnesses.

ANTON RUZICKA.

Witnesses:

JOHN A. BOMMARDT,
J. B. DAVIS.
